H. K. HYRUP

WRENCH

Filed Sept. 16, 1925

Fig. 3.

Fig. 4.

Inventor:
Hans K. Hyrup.
By Martin J. Guich, Atty.

UNITED STATES PATENT OFFICE.

HANS K. HYRUP, OF LOS ANGELES, CALIFORNIA.

WRENCH.

Application filed September 16, 1925. Serial No. 56,711.

My invention relates generally to wrenches and more particularly to a wrench of relatively large size and which is especially adapted for use on the pipe tubes and casing 5 of oil wells although the wrench when made in smaller sizes is applicable for general mechanical uses.

The principal objects of my invention are to generally improve upon and simplify the 10 construction of the existing forms of similar wrenches, to provide a wrench that has a comparatively wide range of adjustability in order that it may be readily used on pipes and casings of different sizes as well 15 as on bolt heads and nuts of different sizes, to provide a wrench of the character referred to that may be very securely engaged and gripped upon the pipe, nut or bolt that is to be manipulated and further to provide a 20 wrench that is of strong, rugged construction and well able to withstand the rough usage to which it is ordinarily subjected.

With the foregoing and other objects in view, my invention consists in certain features of construction and arrangement of parts that will hereinafter be more fully described and claimed and illustrated in the accompanying drawings, in which—

Fig. 1 is a side elevational view of a 30 wrench constructed in accordance with my invention and with parts thereof in vertical section.

Fig. 2 is a plan view of the wrench.

Fig. 3 is an enlarged vertical section taken 35 on the line 3—3 of Fig. 1.

Fig. 4 is an enlarged detailed section taken on the line 4—4 of Fig. 1.

Referring by numerals to the accompanying drawings which illustrate the preferred 40 form of wrench, 10 designates a fixed jaw, the rear portion of which is divided by a vertical slot 11 so as to provide a pair of side walls and the rear portions of these side walls are extended for a suitable distance to 45 provide a handle 12, the outer end portion of which is made U-shaped in cross section as designated by 13. Seated in the under-side of the forward end portion of jaw 10 is a hardened metal block 14 that occupies an 50 angular position and the under face thereof, which is adapted to engage the work, is toothed or serrated as designated by 15.

Adjustably arranged in the opening 11 is the shank portion 16 of a substantially L-shaped jaw 17, the lower portion of which 55 occupies an angular position parallel with

the plane occupied by the angularly disposed end of jaw 10, and seated in the upper face of jaw 17 is a hardened metal block 18 and the upper or work engaging face thereof 60 being toothed or serrated as designated by 19.

The front edge of shank 16 normally bears against a vertically disposed shoulder 20 at the forward end of opening 11 and formed in the front upper portion of shank 16 is a series of notches 21. Pivotedly mounted on a transversely disposed pin or bolt 22 that is seated in the forward portion of jaw 10 is one end of a short dog or adjusting lever 23 65 the opposite end of which is provided with a head 24 that is adapted to occupy any one of the notches 21. Passing vertically through this dog 23 near its forward end is an adjusting screw or bolt 25, the lower end 70 of which bears on a hardened metal disk 26 that is seated in the upper face of jaw 10 directly in front of shoulder 20. Passing transversely through the walls to the sides 75 of opening 11 at the rear end of jaw 10 is a pin or bolt 27 that serves as a fulcrum for a handle 28, which latter lies directly between and over handle 12 and its U-shaped outer portion 13. This handle 28 is slightly 80 longer than the handle 12.

Mounted for rotation in a substantially circular recess 29 that is formed in the forward portion of the head 30 of handle 28 is a hardened metal roller 31 that is adapted 85 to bear against the rear face of shank 16 90 when handle 28 is moved into engagement with handle 12.

When the rear portion of handle 28 is swung upwardly into the position shown by dotted lines in Fig. 1, roller 31 is moved 95 away from shank 16 of the movable jaw and thus the latter may be shifted vertically through the opening 11 either by manipulation of adjusting screw or bolt 25 or by 100 sliding the movable jaw upward a sufficient distance to disengage the head 24 of dog 23 from the notch 21 in which it has been engaged. In the latter event the head of the dog may be re-engaged in one of the notches 21 so that when jaw 17 is moved downward 105 until the end of screw 25 bears on disk 26 the movable jaw will have been adjusted relative to the fixed jaw the distance between two or more notches as the case may be. When handle 28 is again swung downward to engage with handle 12, roller 31 110 bearing against the rear edge of shank 16

will lock the movable jaw to the fixed jaw and the object or work engaged between the blocks 14 and 18 may be turned in the desired direction or held against being turned as the case may be.

Thus the series of notches 21 provides for the adjustment of the movable jaw in a number of different positions and accuracy of adjustment is obtained by proper manipulation of set screw 25 which in bearing on disk 26 raises or lowers the free end of the dog 23 or the end that engages the adjustable jaw.

When the wrench is used in breaking or screwing together the sections of oil well tubing or casing and for other heavy work, the cooperation of the movable handle 28 with the relatively fixed handle 13 enables the wrench to be very effectively manipulated and by properly proportioning the length of said handles the desired purchase or leverage on the engaged object may be readily obtained.

Wrenches of my improved construction are capable of ready adjustment, are of strong, rugged construction, may be easily and cheaply produced and are very effective in performing their intended functions. Obviously minor changes in the size, form and construction of the various parts of my improved wrench may be made and substituted for those herein shown and described without departing from the spirit of my invention, the scope of which is set forth in the appended claims.

I claim as my invention:

1. In a wrench, a handle, a jaw pivotally connected thereto, which jaw is provided with an opening, a substantially L-shaped jaw having one of its legs extending through the opening in the other jaw, the leg of said L-shaped jaw that projects through said opening being provided in its front face with a series of notches, a member pivotally and adjustably mounted upon the jaw that

is pivoted to the handle for engagement in the notches in the leg of said L-shaped jaw and a member carried by the pivoted end of the handle for engaging the L-shaped jaw and locking the same to the jaw that is carried by the jaw to which said handle is pivoted.

2. In a wrench, a jaw provided with an opening, a handle formed integral with one end of said jaw, a second handle pivotally connected to said jaw between said opening and the integral handle, a substantially L-shaped jaw having its shank portion extending through the opening in the first mentioned jaw, the front edge of the shank of said L-shaped jaw being provided with a series of notches, a member pivotally mounted upon the first mentioned jaw and adapted to engage one of the notches in the shank of the L-shaped jaw, means carried by said pivotally mounted member for adjusting the position thereof on the jaw to which said member is pivoted, and means on the inner end of the pivoted handle for bearing against the rear edge of the shank of the L-shaped jaw to lock the two jaws to each other.

3. In a wrench, a jaw provided with an opening, a substantially L-shaped jaw having its shank portion extending through the opening in the first-mentioned jaw, the shank of the L-shaped jaw being provided on its forward edge with a series of notches, a member pivotally and adjustably mounted upon the first mentioned jaw and adapted to occupy one of the notches in the shank of said L-shaped jaw, a handle pivotally connected to the first mentioned jaw to the rear of the opening therein and an anti-friction member loosely mounted on the forward end of the handle for engagement with the rear edge of the shank of the L-shaped jaw.

In testimony whereof I affix my signature.

HANS K. HYRUP
